APPARATUS FOR TREATING SOLID MATERIALS

Filed Feb. 24, 1925

UNITED STATES PATENT OFFICE

WILLIAM A. DARAH, OF CHICAGO, ILLINOIS

APPARATUS FOR TREATING SOLID MATERIALS

Application filed February 24, 1925. Serial No. 11,262.

This invention relates to processes of treating material and the equipment for carrying out said processes. One specific application of the process is the coking of mixtures of coal and oil, although many other applications will be apparent.

For example, the equipment may be used in the cooking of certain food products, the drying or baking of a wide range of materials such as cores for foundry use, as well as the drying and distillation of coal, peat, wood or other materials.

The process and equipment are particularly suited for the treatment of those materials which contain water or other volatile material in the raw condition, and which give off volatile materials during some portion of the heating or baking process.

For example, equipment of this kind may be employed in the manufacture of such articles as linoleum, oil compositions, oil-cloth, etc.

The process and apparatus will be described particularly in connection with its application to low temperature distillation of coal mixed with oil, but it should be understood that while this is one highly satisfactory application, many other substances may be treated in a like manner.

In the process of making an artificial fuel it has been customary to finely pulverize coal in the presence of water and then agitate the mixture with some relatively heavy oil, when the coal and oil will agglomerate, leaving the water and a considerable part of the ash in the form of a slime or solution which can be readily separated from the coal and oil. I do not claim to have invented the above process, which has been quite thoroughly developed by others.

The process described above, however, leaves a material which is soft, relatively plastic and usually sticky. Such a product cannot be handled to advantage without changing its condition or wrapping it in

coverings such as paper, etc. In any case, the water which it contains, frequently running to 10 or 15 per cent, represents a loss unless it is removed prior to combustion. The object of this invention is to provide a process and equipment for treating the mixture of coal and oil (and such other materials as will be evident) in such a way as to remove the water and to leave a hard, firm residue which may be readily handled commercially.

In the treatment of material of this kind there will be a considerable amount of volatile material given off. The nature and quantity of the volatile material will naturally depend on the character of the ingredients, such as the coal and fuel oil, as well as upon the temperature to which the materials are subjected, the rate of heating and conditions of heating.

For example, in the case of mixtures of coal and fuel oil, the amount of moisture to be removed will frequently amount to or exceed 15 per cent by weight, and the amount of volatiles removed may frequently range from 5 to 15 per cent by weight.

The volatile materials removed will contain hydrogen, ethylene, methane, and various gaseous hydrocarbons as well as some of the condensable hydrocarbons such as benzine, gasoline, and the related products. Ammonia is frequently given off during distillation. On raising the temperature to higher figures naturally the heavier oils and tars will be collected with the volatile materials, but these will not be present in large quantity ordinarily in low temperature distillations.

It will be observed that the volatile materials in this case combine both the volatiles which would be given off by the distilling of the coal as well as the volatiles which would be given off by the distilling of the oil. In addition, there appears to be a catalytic action or some interaction between

the powdered coal, the water vapor and the oil compounds which frequently cause a greater production of volatiles from the combined mixture than would be obtained by the distillation of the various ingredients separately. There also appears to be a distinctive difference between the character of the volatile materials given off when the mixture is distilled, and the character of the distillation products of the various materials which compose the mixture, when treated separately.

I have found that the distilling of the mixture of powdered coal, water and oil, gives most satisfactory results when the amount of water is reduced to a minimum. For example, 1 per cent or less of water in the mixture of oil, coal and water, will give much better results from the distillation standpoint than the original combination as it is produced after grinding, which may contain 15 per cent water.

Another factor of importance in this connection is that the removal or evaporation of the water is an operation which requires the transfer of a considerable amount of heat. For example, each pound of water evaporated requires the transfer of approximately 1000 B. t. u. Such a heat transfer can readily be obtained by means of convection, in which hot gases or air are brought into contact with the moist material, and heat transferred by this means involves a relatively small temperature difference. On the other hand, if it is attempted to evaporate the water by subjecting the moist material to radiant heat, or by merely passing it through a hot chamber, the temperature difference would be extremely high, the efficiency correspondingly reduced, the losses through the walls of the apparatus correspondingly greater, and the life of the equipment would be proportionately less.

Incidentally, if the water contained in the material were driven off at the same time that the volatile materials were driven off, as would of course be the case in passing the wet material into a hot chamber, the condenser employed to liquefy the volatile products would have to be much larger and the cooling medium would be required to do correspondingly more work.

I have also found that when the water is removed by heating the entire mixture in a hot chamber, the process cannot be controlled and the final product is likely to be overheated. Further, the hot water vapor has a noticeable tendency to react with some of the materials present, causing permanent gases and breaking down substances which would otherwise be of value. In other words, the amount of fixed gases is higher and the yield of valuable by-products is reduced when the material is distilled with the moisture present.

To overcome these difficulties I have developed an equipment as shown on the drawings and the process which may be carried out with this equipment.

Referring to the drawings, Figure I shows a sectional side elevation through one form of my invention, while Figure II shows a plan view in section, the section toward the discharge end being taken through the combustion chambers.

Referring to the drawings, (1) indicates a shell or container which may be made of any suitable material and which can conveniently be constructed of a steel shell (2) lined with brick (3) and preferably insulated. In the drawings the brick (3) serve as the insulation. Within the housing (1) is supported a conveyor (4) of any suitable form. In the form shown the conveyor consists of a series of sprockets (5, 6, 7, 8) carried on shafts (9, 10, 11 and 12). The said shafts may be mounted on bearings in any suitable manner. A perforated conveyor of suitable material to withstand the operating temperatures is provided to pass over the sprockets is shown by (13). The conveyor bottom should either be perforated or made from expanded metal, netting or similar material, although this is not absolutely essential. The material to be treated may be fed onto the conveyor through hopper (14), located at the entering end, and is discharged from the conveyor to hopper (15), from whence it may be conveyed to the proper stock pile, bin or storage space.

In the construction shown on the drawings, a floor (17) is provided, extending substantially horizontally the length of the furnace. The floor may be supported on I-beams (18) or in any other suitable manner, depending on local conditions. Upon the floor (17) are located a series of combustion chambers (19) which serve as muffles in which the fuel used to heat the oven is burned. The muffles may be made of carborundum, alundum, or other suitable refractory material, and while they are shown extending transversely across the length of the oven, they may of course be placed in any desired relation to the conveyor. Two radiation walls, (20 and 21) are placed one on each side of each combustion chamber and provided with a series of inlet ports (22 and 23) at their lower edge, so arranged that the gases adjacent to them can readily pass through the lower edge of the wall and upward in the space between the reflecting wall and the combustion chamber.

The return of the conveyor is shown diagrammatically as beneath the floor (17) and indicated by reference numeral (24).

The combustion chambers are provided with burners (25), which may be arranged

to burn oil, gas, powdered coal, or any desired fuel.

The various combustion chambers are arranged in such a manner that the products of combustion leaving them pass through a restricted opening (26) into a common flue (27) which conducts the products of combustion to a distributing flue (28). Flue (27) is completely covered at its top portion by wall (40) as shown in dotted lines in Fig. I. The only outlet, therefore, from flue (27) is at its extreme end where it discharges into cross flue (28), which it will be noted is beyond and outside of the distillation chambers closed by the seals indicated by numeral (35A). There is no direct connection between the distilling chambers and the flue (27). The outlet of flue (28) is beneath the conveyor chain and extends a substantial portion in a transverse direction across the width of the chain. An exhauster (29) is located near the entering end of the oven and arranged so that its intake (30) will draw the products of combustion from distributing flue (28) along the conveyor chain and through the perforated conveyor (13), thus bringing the hot products of combustion into intimate contact with the cold incoming material.

Ports (34A) are provided in distributing duct (28) to permit the addition of cooling air in case the products of combustion from the combustion chambers (19) are too hot.

The products of combustion and air will pass through the perforated conveyor (13) and under and over the material to be heated, as well as through the interstices between the lumps of material, and then out of exhauster (29).

It will be apparent, however, that the material which is treated enters through chute (14) in a layer onto conveyor (13), where it is subjected progressively to the hot gases from the products of combustion. The flow of material to be treated and the products of combustion and hot air is counter-current.

A series of partitions (32, 33, 34, 35, etc.) are provided to divide the treating chamber into a series of individual chambers sealed from each other as far as possible except at the point through which the conveyor passes. Additional means are provided to assist in securing a tight seal, such as loose fingers (35A), pivoted above the conveyor and adapted to drag on the surface of the material on the conveyor. A similar arrangement is provided underneath the conveyor to close the air spaces at this point. It will be apparent that the chambers are not hermetically sealed one from the other, but are closed so tightly that with the pressures available the leakage will be small.

As the material to be treated leaves the preliminary drying chamber, where it has

been in contact with the rapidly moving stream of hot air and products of combustion, it will have been raised in temperature somewhat, possibly up to 200 degrees F. or even higher, although the exact figure is not essential. At the same time that the temperature of the material has been raised the water has been removed and the material will be relatively quite dry when it enters the first treating chamber. In the first treating chamber the material will be subjected to the convected and radiant heat from the combustion chamber (19), and the distillation of the volatile materials and the baking of the product will begin. As the conveyor continues its travel, baking will progress and with it the distillation of such volatile materials as can be driven off. At the end of the travel of the conveyor, the material which has been treated and dried will fall into hopper (15) where it will pass to a stock pile or storage bin. The conveyor will return beneath the floor (17) to the entering end of the oven where the cool material will be loaded onto the warm conveyor. The process, it will be noted, is continuous, and subjects the materials to be treated, first to a drying and heating process which also frequently forms a skin or coating. The later steps in the process constitute a baking and coking, or distillation.

The action in forming a skin or layer is not essential but is very important in this connection, particularly with certain materials which have a tendency to soften and stick together unless given a preliminary surface drying and surface hardening, as described.

The moisture which has evaporated from the material being treated, naturally passes out with the warm air and products of combustion and is exhausted into the air.

On the other hand, the volatile products which are of value are collected in header (36) from intakes (37, 38 and 39), which preferably pass a sufficient distance into header (36) to form a water seal.

It will be apparent that as the conveyor passes progressively over the various combustion chambers the material will be heated to progressively higher temperatures, the heating process being of course gradual, and under complete control both as to rate of heating and final temperature. For example, if it is desired to heat quickly, the combustion chamber nearest to the cold end of the conveyor would be heated as hot as possible by the combustion of the maximum amount of fuel, while the succeeding combustion chambers would have their burners turned down somewhat and burn less fuel, thus contributing less heat to the material on the conveyor.

On the other hand, if it is desired to heat slowly and gradually, the combustion cham-

ber nearest to the end would be operated with lower rates of fuel consumption and the succeeding combustion chambers would be supplied with a greater amount of fuel.

5 Automatic controls may of course be supplied on each of the combustion chamber burners to control the rate of feed of fuel and the admission of air. In many cases such automatic control will not be necessary,

10 as simple hand control will hold a temperature substantially constant with a small amount of attention. It will be noted that in this case control means are provided, although they would not be automatic.

15 Damper (31A) also provides a control, inasmuch as by opening it a controlled temperature reduction takes place in the products of combustion in flue (28), thus reducing the temperatures to which the cool, wet

20 materials are subjected.

There will occasionally be times where it is desirable to separate the volatile products which are taken off from the various combustion chambers. The advantage of 25 this will of course be evident when it is considered that the volatiles given off in the chambers near the entering end of the conveyor are the result of lower distillation temperatures and will therefore represent

30 more volatile products. On the other hand, the volatile materials given off in the chambers near the discharge end of the conveyor will represent higher boiling point compounds, and also, therefore, a certain amount 35 of cracking, which will involve more fixed gases. I have found also that the chemical nature of the distillation products is different in the different combustion chambers.

Under some conditions it is economical to 40 use noncondensable products of combustion as the source of fuel for heating some or all of the combustion chambers. This is purely of course a matter of economies; depending upon the relative values of fuel and the distillation products.

When the mixture of finely ground coal 45 and oil is passed through the equipment described in the specifications, it has the appearance somewhat similar to a close grain-
50 ed, strong coke. Naturally, the general appearance and characteristics as well as the analysis will depend upon the materials used and the operating temperatures. If the material is fed onto the conveyor in the form

55 of cylinders or balls, it will of course be permanently set in this shape. The cohesion of the particles in the briquette thus formed is excellent and the fuel has very desirable properties, due to its purity, its 60 uniformity, its structure and its composition.

It will be apparent that many modifications in the process and apparatus here disclosed may be made without departing from 65 the spirit of this invention, thus the length

and time of travel of the conveyor may be varied. In actual operation I have found a speed of from 1 to 2 ft. per minute gives good results, but naturally this speed will depend not only upon the nature of the 70 materials but also upon the operating temperature, the heat transfer, and other obvious factors.

The drying period will of course be varied to suit the actual operating conditions. I 75 have found that in many cases a drying period of from 30 to 40 minutes gives excellent results, but obviously I do not wish to be held to this figure, as the size of the particles being dried, the amount of moisture content, the porosity of the particles, etc., radically affect the drying period.

In the same way, the number and size of combustion chambers is a variable, depending upon the output required, desired operating temperatures, and other well known factors. I may employ only one combustion chamber or I may employ many. I have found that under commercial conditions six or seven combustion chambers give 90 good results, but obviously the output and size of the equipment will determine the number employed.

It will be noted that the process and equipment here disclosed permits the handling of materials which are relatively soft or plastic, without jarring them, dropping them or disturbing them. This is of considerable importance in the case of many classes of materials which are relatively soft 100 prior to the drying and baking.

In using the term "perforated" I intend to designate a surface having a number of openings or holes. It should be understood that I do not confine myself to any particular form or arrangement of holes, as they may obviously be slots, openings between adjacent sheets or have any configuration such as square, round, oblong, oval, etc. 105 As set forth, the object of the perforations is to permit a movement of the heated gases through the conveyor and any construction which accomplishes this result comes within the scope of my invention.

Having now fully described my invention, 110 what I claim as new and wish to secure by Letters Patent in the United States, is as follows:

Claims:

1. An apparatus for heat treating solid materials which consists of an elongated housing, containing a preheating chamber and a heating chamber, means separating said preheating chamber from said heating chamber, an endless longitudinally extending conveying device for carrying said material within said housing, a muffled combustion chamber arranged transversely of said conveying device and spaced therefrom to supply radiant heat to said materials on 120
2. An apparatus for heat treating solid materials which consists of an elongated housing, containing a preheating chamber and a heating chamber, means separating said preheating chamber from said heating chamber, an endless longitudinally extending conveying device for carrying said material within said housing, a muffled combustion chamber arranged transversely of said conveying device and spaced therefrom to supply radiant heat to said materials on 125
3. An apparatus for heat treating solid materials which consists of an elongated housing, containing a preheating chamber and a heating chamber, means separating said preheating chamber from said heating chamber, an endless longitudinally extending conveying device for carrying said material within said housing, a muffled combustion chamber arranged transversely of said conveying device and spaced therefrom to supply radiant heat to said materials on 130

said conveying device, and a duct connecting said muffled combustion chamber to said preheating chamber to direct the products of combustion from said muffled combustion chamber to said preheating chamber.

2. A device for heat treating solid materials containing volatile matter, consisting of endless longitudinally extending equipment for moving the material, a preliminary 10 drying chamber, and heating chamber adjacent to said said drying chamber, seals between said heating chamber and said drying chamber, a closed longitudinally extending combustion chamber spaced from said moving equipment for heating said heating chamber by radiation, and a duct for connecting said drying chamber with a means for supplying hot gases.

3. A device for treating solid materials 20 consisting of a longitudinally extending endless conveyor for carrying said materials, a preliminary drying chamber through which said conveyor travels, a heating chamber adjacent it, but separated from said 25 drying chamber through which said conveyor travels, a muffled transversely extending combustion chamber located in said heating chamber and spaced from said conveyor and a duct for delivery of hot gases from said 30 combustion chamber through said conveyor and said material therein, while in said drying chamber.

4. In a device for heat treating solid materials a preheating chamber, a treating 35 chamber, an endless longitudinally extending conveyor arranged to carry said material being treated through said chambers, a closed combustion chamber arranged transversely to said conveyor and spaced 40 therefrom to radiate heat to said conveyor, but to keep products of combustion from said combustion chamber out of contact with said conveyor in said treating chamber and a duct to connect said combustion chamber 45 to said preheating chamber.

5. In a device for heat treating solid materials, a heating chamber containing a conveyor of an endless structure extending longitudinally therein for carrying materials, 50 a closed combustion chamber separated therefrom, but arranged transversely to said conveyor, but spaced therefrom to radiate heat to said conveyor, and a duct connecting the discharge of said combustion chamber with a preheating chamber near the point at which said conveyor enters said heating chamber.

6. A device for treating solid materials 60 consisting of an elongated housing, a loading device, an endless conveyor extending longitudinally within said housing for carrying said materials, a muffle arranged within said housing transversely to said conveyor to give off radiant heat to said conveyor, a duct connecting the discharge of

said muffle to the entering portion of said heat treating device and a chamber connected to said duct and surrounding a portion of said conveyor adjacent said loading device.

7. In a device for heat treating solid materials a longitudinally extending housing, a conveyor for carrying said materials, a refractory combustion chamber arranged adjacent to said conveyor and within said 70 housing and spaced from said conveyor, radiation receiving surfaces adjacent said combustion chamber, but spaced away therefrom, said radiation receiving surfaces having ports for permitting a relatively 75 free circulation of the gaseous medium within said housing around said conveyor and along said radiation receiving surfaces and said combustion chamber and in contact with said conveyor.

8. In a device for heat treating solid materials, an elongated housing, a conveyor therein, a refractory combustion chamber arranged adjacent to said conveyor but spaced therefrom, substantially vertical 80 walls adjacent said combustion chamber for receiving radiation therefrom, said walls being spaced away from said combustion chamber to afford a relatively free passage 85 for the circulation of the gaseous contents of said housing along said walls and combustion chamber and in contact with said conveyor.

9. A device for heat treating solid materials, consisting of a drying chamber and 100 a heating chamber sealed from said drying chamber, a longitudinally extending conveyor extending through both, said heating chamber being supplied with a muffled source of radiant heat while said drying chamber is supplied with the products of 105 combustion from said muffled source, and a duct extending substantially longitudinally of said device connecting the outlets of said muffled source of radiant heat with a chamber adjacent the cooler end of said perforated conveyor.

10. A heat treating device for solid materials consisting of an elongated housing, a conveyor therein, a preheating chamber, and 115 a heating chamber in said housing, separating means between said heating chamber and said preheating chamber, a transversely extending muffled combustion chamber spaced from said conveyor for supplying 120 radiant heat to said heating chamber, and a duct connecting said muffled combustion chamber with said preheating chamber.

11. A device for heat treating solid materials consisting of an elongated housing, a 125 device for delivering material to one portion of said housing and a device for discharging material at another portion of said housing, a preheating chamber in said housing adjacent said device for delivering 130

material, a heating chamber adjacent said preheating chamber, a longitudinally extending conveyor arranged to carry material through said device and through said chambers, means for separating said preheating chamber from said heating chamber, a closed transversely extending combustion chamber spaced from said conveyor, but arranged to supply radiant heat to said heating chamber, and a duct arranged to convey the products of combustion from said closed combustion chamber to said preheating chamber.
